UNITED STATES PATENT OFFICE.

LOUIS EGGER, OF SUMMISWALD-GRUNEN, SWITZERLAND.

THREAD-CLAMPING DEVICE.

Original application filed December 21, 1921, Serial No. 523,989. Patent No. 1,450,914, dated April 10, 1923. Divided and this application filed December 4, 1922. Serial No. 604,920.

To all whom it may concern:

Be it known that I, LOUIS EGGER, a citizen of Switzerland, residing at Summiswald-Grunen, Switzerland, have invented certain new and useful Improvements in Thread-Clamping Devices, of which the following is a specification.

The present invention has reference to improvements in sewing machines and relates 10 more particularly to an improved clamping device for periodically clamping the stitching thread against being drawn out further under the operative pull. A clamp of this character is used to advantage in connection with 15 a book sewing machine such as described in my application filed December 21, 1921, Serial No. 523,989 and which has matured in Patent No. 1,450,914, April 10, 1923 in which this invention was first disclosed and of 20 which this application forms a division, but it may, obviously, also be used in other connections.

My invention will best be understood when described in connection with the accompanying drawing, in which Fig. 1 is a front view of the device; Fig. 2 is a fragmentary top view, and Fig. 3 a section on line 3—3 of Fig. 1; Fig. 4 shows the clamping device in section with its drive, in position on suitable supporting means.

The cross-bar 1 is rigidly mounted between the lateral machine frame standards 2 and 3 and is provided with a plurality of housings 4 presenting downwardly tapering bores 44, the number of which depends upon the number of stitching units used in the particular machine. With these bores cooperate truncated cone shaped plugs 5 in such manner that in their lowermost operative 35 position they fit the bore tightly all round. The bore walls are slit open at one side, as at 6, to present thread introducing passages 7. For more conveniently introducing the threads, always two such passages 7 may be 40 arranged facingly, as shown in Fig. 2, but it must be understood that this particular arrangement is not necessary and the slits may be in any other relative position, as long as they will permit the ready introduction of the 45 thread which, prior to entering the passage, passes through the tensioning device 8 of well known construction. The thread, after having been introduced into the bore through the slit 7, is guided around the lifted plug 50

to some extent to prevent it from slipping out again.

From the top of each plug extends a guide pin 9 adapted to freely reciprocate within a bridge member 10 extending from the cross-bar 1, and an interposed compression spring 60 11 serves to normally retain the plug pressed home in its seat, as clearly shown in the several figures. The referred-to tensioners 8 are preferably all mounted on the bridge member 10. For periodically simultaneously and uniformly operating the plugs there is provided a swing bar 12 fulcrumed at 13 and 14 respectively at its extremities on bearing cheeks 15 and 16 extending from the cross-bar 1, which swing bar is in operative contact with the lower faces of all of the plugs. Rocking movement is imparted to this swing bar in any suitable manner, for instance as shown, by means of a bell crank 17, whose outer arm 21 coacts with the lower end of the swing bar, and whose inner arm 22 is acted on by a bell crank 18 by the intermediary of the connecting link 19. This bell crank 18 is pivoted at 25 on the machine frame and its inner roller end 26 is operated by a cam 20. On rotation of the latter, which preferably is fixed on the main drive shaft 23, the bell crank 17 is rockingly operated and in turn oscillates the swing bar for alternately lifting the plugs and letting them down again into their seats for respectively freeing the threads and then again temporarily securely clamping them against operative pull.

In order to vary, within limits, the lift of the plugs, the arm 21 of the bell crank 17 is provided at its free end with an adjusting screw 24.

Obviously, the described means for operating the swing bar may be provided at both ends thereof close to each side support.

The described mechanism forms a complete unit and can readily be mounted on a machine in exchange for a less satisfactory or worn out thread clamping device, the swing bar being capable of being operated in any other suitable manner than in that shown by way of example.

What I claim is:

1. In a thread clamping device of the character set forth, in combination with suitable supporting means, a cross-bar rigidly mounted on said supporting means, a plu-

- rality of housings on said cross-bar presenting downwardly tapering bores, plugs adapted for reciprocal cooperation with said bores, means for normally independently retaining said plugs in their operative, thread clamping position, and means for periodically uniformly lifting them off their seats, each of said housings being split down its one side for thread introducing purposes.
- 10 2. In a thread clamping device of the character set forth, in combination with suitable supporting means, a cross-bar rigidly mounted on said supporting means, a plurality of housings presenting downwardly tapering and laterally slit bores in said bar, a bridge member rigidly secured to said cross-bar, a cone shaped plug for each housing, a guide pin extending from each plug and a compression spring surrounding said guide pin, the latter adapted to be guided in said bridge member, a thread tensioner on said bridge member for each housing, and means for periodically uniformly lifting all of said plugs.
- 15 3. In a thread clamping device of the character set forth, in combination with suitable supporting means, a cross-bar rigidly mounted on said supporting means, a plurality of laterally slit housings presenting downwardly tapering bores on said cross-bar, a bridge member rigidly secured to said cross-bar, thread tensioners on said bridge member, plugs adapted for reciprocal cooperation with said housing bores and means for normally independently retaining said
- 20
- 25
- 30
- 35

plugs in their relative clamping position, means for periodically uniformly lifting all of said plugs, comprising a swing bar pivotally mounted relative to said cross-bar and in operative contact with the lower faces of said plugs, means for imparting to said swing bar an oscillatory movement, and means for varying the operative lift of said plugs.

4. In a thread clamping device of the character set forth, in combination with suitable supporting means, a cross-bar rigidly mounted on said supporting means, a plurality of laterally slit housings presenting downwardly tapering bores on said cross-bar, a bridge member rigidly secured to said cross-bar, thread tensioners on said bridge member, plugs adapted for reciprocal cooperation with said housing bores and means for normally retaining said plugs in their relative clamping position, means for periodically lifting said plugs, comprising a swing bar in operative contact with the lower faces of said plugs, a bell crank pivoted on said supporting means, one arm of which coacts with said swing bar, an adjusting member on this bell crank arm, a main drive shaft, a cam fixed thereto, a second bell crank pivoted on said supporting means and operable by said cam, and a connecting link between said cam operated bell crank and said swing bar operating bell crank.

In testimony whereof I affix my signature.

LOUIS EGGER.
